COMBINED CLOTHES RACK AND STORAGE SHELF UNIT

Michael Schachel, Shadow Ridge Road,
Franklin Lakes, N.J. 07417

Filed Nov. 27, 1970, Ser. No. 26,183

Term of patent 14 years

Int. Cl. D6—04

U.S. Cl. D6—189

FIG. 1.

FIG. 4.

FIG. 2.

FIG. 3.

FIG. 6.

FIG. 5.

FIG. 1 is an enlarged perspective view of a combined clothes rack and storage shelf unit showing my design; FIG. 2 is a front elevational view thereof;

FIG. 3 is a top plan view thereof;

FIG. 4 is a side elevational view thereof;

FIG. 5 is a rear elevational view thereof; and

FIG. 6 is a modified form of the combined clothes rack and storage shelf unit of FIG. 1 on a reduced scale.

The back and side not shown in FIG. 6 are plain and unornamented.

I claim:

The ornamental design for a combined clothes rack and storage shelf unit, substantially as shown and described.
